Patented Nov. 10, 1914.

UNITED STATES PATENT OFFICE.

FRANK DOWD, OF CLEVELAND, OHIO.

ROLLER-PLATEN FOR TYPE-WRITING MACHINES.

1,116,395.

Specification of Letters Patent. Patented Nov. 10, 1914.

Application filed August 8, 1913. Serial No. 783,664.

To all whom it may concern:

Be it known that I, FRANK Dowd, a citizen of the United States, residing at Cleveland, in the county of Cuyahoga and State of Ohio, have invented certain new and useful Improvements in Roller-Platens for Type-writing Machines, of which the following is a specification.

This invention has reference to an improvement in roller platens for typewriting machines, and the object of the invention is to provide a platen or roll which is materially cheapened as compared with platens as hitherto made and also is improved in character because it is compartmented throughout with dead air spaces and walls between said spaces which will not transmit sound, all substantially as shown and described and particularly pointed out in the claims.

In the accompanying drawings, Figure 1 is an elevation of the roll or platen partly sectioned away at one end to disclose inside construction. Fig. 2 is a sectional elevation of one end of a modified form of the platen, and Fig. 3 is a sectional elevation of one end of still another modification thereof.

The essential principle of the roll or platen thus shown is to have dead air spaces or compartments distributed throughout the body thereof from end to end and to occupy as much of the roll as possible consistent with suitable sustaining walls for the covering or shell for said spaces, whereby the sounding board or drum effect is overcome or avoided and the stroke of the keys is deadened as nearly as possible in a roll of this kind. To these ends I build the platen in any one of the several styles shown, or their equivalent.

In Fig. 1 the platen is constructed with a core or body of wood having solid ends 2 and a succession of what may be termed disks or division walls 3 at intervals, the space between said disks being greater somewhat than the thickness of the disks, or thereabout, the idea being to have as much air space as possible and at the same time provide sufficient wall support for the shell of the roll to keep the roll or platen even and firm on its working surface.

The said disks, so-called, are developed by sawing out the stock between them down to the core proper indicated by 4, which has a bore centrally lengthwise through the same from end to end occupied by a shaft *s* on

which the platen as a whole is mounted. The spaces between the several disks constitute so many dead air spaces, chambers or compartments, and there is no communication between them. A key may therefore strike over any one of said spaces or compartments and there will be no sound transmitted to an adjacent compartment. If the key strikes over one of the disks 3 there will be no sound to either side because of the dead chambers or spaces at the sides through which sound will not carry, and thus as a platen is produced which is practically sound proof and at the same time is exceedingly simple and economical in its make-up.

The cover or inclosing portion as such may be of any suitable material, as, for example, an inner sleeve or cylinder *c* of aluminum, or fabric, or metal and fabric, and an outer tube or cover *b* of a suitable grade and hardness of rubber especially manufactured for this purpose. The rubber employed in platens in everyday use on various makes of machines may be used for this purpose, and while such rubber will resist continuous hammering by the keys for a long period of time it is a practically dead element when engaged over the inner sleeve *c* and the compartmented body within the same as shown and described herein. The same is true as to each and all the forms of the platen comprised in my invention. Thus, in Fig. 2, I show a body with spirally disposed division walls 6 spaced apart relatively as in Fig. 1 and running continuously from end to end of the roll. The dead air spaces between these walls operate in effect as the like spaces between the walls 3 in Fig. 1. In Fig. 3 the body of the platen likewise is preferably made of wood and cut with radially disposed walls 8 lengthwise terminating at the heads 2. The said walls are spaced apart by intervening air spaces 100 alternately disposed with the said walls and each space or compartment is co-extensive with the said body between the solid ends 2.

The construction in Fig. 3 has the material advantage of always bringing the stroke of the keys upon or over the dead air pockets, and this result is obtained by making the teeth 7 coincident with the said air spaces, the said teeth determining the stopping points of the roll and the measure of forward movement thereof. It follows that

the stroke of the keys always comes between the ribs or walls.

What I claim is:

1. A platen for typewriting machines having a core of wood and a series of integral walls radiating from said core, said walls having dead air spaces between them their full depth to said core and said spaces separated by said walls, the said core having a bore longitudinally through the center thereof, a shaft fixed in said bore and end supports for said core having tubular extensions sleeved over said shaft.
- 10 2. A platen for typewriters having a body constructed with a core provided with a bore lengthwise through the same and a

series of radially disposed walls integral with said core and extending lengthwise in parallel lines and said walls divided one from the other by dead air spaces their entire depth, an inner tube sleeved upon said walls and an outside tube sleeved on said inner tube, the said body having solid end portions closing said dead air spaces at their ends. 25

In testimony whereof I affix my signature in presence of two witnesses.

FRANK DOWD.
